Patented Feb. 16, 1926.

UNITED STATES PATENT OFFICE.

JOHN ROBERT CAMPBELL, OF REGINA, SASKATCHEWAN, CANADA.

COMBINED FLOOR WAXER AND POLISHER.

Application filed July 31, 1922. Serial No. 578,722.

To all whom it may concern:

Be it known that I, JOHN ROBERT CAMPBELL, a subject of the King of Great Britain, a resident of the city of Regina, in the Province of Saskatchewan, Canada, have invented certain new and useful Improvements in Combined Floor Waxers and Polishers, of which the following is the specification.

10 My invention relates to improvements in combined floor waxes and polishers and the object of the invention is to devise means for alternately driving the rotary waxing pad or a polishing brush from an electric 15 motor, as the device is pushed along the floor.

A further object is to devise means whereby the pad and brush can be readily changed as occasion demands.

20 A still further object is to devise a simple and effective means for attaching the waxing pad to a drum.

My invention consists of a combined floor waxer and polisher constructed and arranged all as hereinafter more particularly described and illustrated in the accompanying drawing in which:

Fig. 1 represents a perspective view of a device constructed according to my invention, showing the cover broken away to show the working parts.

Fig. 2 is a front view of the device showing the same broken away and the brush just being released.

Fig. 3 is a similar view to Figure 2 showing the brush replaced by the pad.

Fig. 4 is an enlarged elevational detail of one end of the drum carrying the waxing pad, showing the means for attaching the pad to the drum, and

Fig. 5 is a plan view of the waxing pad.

Like characters of reference indicate corresponding parts in the different views.

1 is the cover of the device which is adapted to be provided with the bale 2 suitably hinged thereto, said bale 2 having the upwardly extending handle 3 connected therewith. The bottom of the cover 1 is provided with a frame-work composed of laterally extending bars 4 upon which is supported the motor 5 provided with the driving pulley 6. 7 are castors provided on the bottom of the cover 1 for supporting the device on the floor. 8 is the driven pulley mounted on the spindle 9 which extends through the bosses 10 in one side of the cover 1 and is

journalled therein, said spindle being held in position by means of the collar 11. The inner face of the driven pulley 8 is provided with a squared hole 12 adapted to receive 60 the squared end 13 of the drum 14, or the brush 15, depending on whether the pad or brush is in use. The opposite side of the cover 1 is provided with the inwardly extending threaded stud 16 which has a reduced inner end 17 adapted to be inserted into a hole 18 in the opposite end of the drum or brush, the outer end of such stud being suitably enlarged and knurled. 19 are flanges on the ends of the pad drum 70 provided with suitably disposed hooks 20 on which are hooked the loops 21 of the pad 22, which is adapted to extend around the pad drum 14.

23 is a belt extending between the drive 75 pulley 6 and the driven pulley 8.

24 are the leads from the motor 1 extending up through the cover 1 along the bale 2 and up the handle 3, being provided with the usual switch on the handle to control 80 the operation of the motor, such switch not being shown as it is common to devices of this nature and vacuum cleaners.

The operation of my device is as follows:

When it is desired to wax the floor the 85 wax is spread on the pad 22, where such wax is in the form of paste. If the wax is in liquid form the pad would be dipped into the same. The pad is then applied to the drum 14 in the manner shown in Figure 3, 90 the loops 21 of the outer and inner ends being looped over the corresponding hooks on the ends of the flanges 19. My device is now run over the floor, the motor being turned on and the floor thoroughly waxed. 95

When this is done, by unscrewing the stud 16 by means of the enlarged knurled head, the inner ends 17 thereof will be disengaged from the hole 18 in the drum and such drum can be pulled longitudinally until the squared end 13 is released from the square hole 12 in the driven pulley, when such drum can be replaced by the brush 15 which is placed in position by reversing the above mentioned operation. The floor is then polished with the brush. If an exceptionally good surface were required a polishing pad could be used constructed in exactly the same manner as the waxing pad, but placed on the drum in a dry condition.

110 From the above description it will be seen that I have devised a simple and effective

combined floor waxer and polisher in which the waxing means and polishing means will be readily interchangeable.

Further I have constructed a device in which the number of parts will be exceedingly small and in which the device can be constructed at a comparatively small cost.

What I claim as my invention is:

In a floor waxer and polisher, the com-

bination with a rotatable drum, of a flat pad 10 adapted to be rolled around the drum, loops at the corners of the pad, flanges on the ends of the drum, hooks on the inner faces of the said flanges, said pad adapted to be rolled around the drum and the loops at 15 the inner and outer ends thereof hooked over the respective hooks.

JOHN ROBERT CAMPBELL.
